TOBACCO PIPE

Francis P. Ellsworth, New York, N. Y.

Application February 6, 1934, Serial No. 709,940

7 Claims. (Cl. 131—12)

The present invention relates to improvements in tobacco pipes, and has for its purpose the provision of a pipe that gives a uniformly mild smoke from beginning to end, instead of a progressively stronger smoke as is the case with ordinary pipes. Another purpose is to provide a pipe in which all of the tobacco may be readily burned and in which the tobacco in the bottom does not become saturated with moisture, allowing a longer and more economical smoke.

Still another purpose is to provide a pipe that is arranged so that the moisture, nicotine and other volatile products in the smoke are partially condensed in passing through the pipe and disposed of in such a way that they are not drawn into the smoker's mouth, or do not tend to block the smoke passage. A further purpose is to provide a pipe which imparts to the smoke an exceptionally pleasant flavor, and which smokes mildly from the first smoke and requires no objectionable breaking in. Another purpose is to provide a pipe of the type described above that is simply and reliably constructed, is easily operated, and readily cleaned.

With the above and other objects in view, embodiments of my invention are shown in the accompanying drawing, and these embodiments will be hereinafter more fully described with reference thereto, and the invention will be finally pointed out in the claims.

In the drawing:

Fig. 1 is a side elevation, with a portion of the pipe bowl broken away of a tobacco pipe according to one embodiment of my invention.

Fig. 2 is a vertical sectional view thereof.

Fig. 3 is a horizontal sectional view, taken along the line 3—3 of Fig. 2.

Fig. 4 is a longitudinal sectional view, taken along the line 4—4 of Fig. 2.

Fig. 5 is a vertical sectional view of a modified form of the invention.

Similar reference characters indicate corresponding parts throughout the several figures of the drawing.

Referring now to the drawing, 10 is the conventional body of the pipe made preferably of briar wood. The inner surface of the bowl part is bored cylindrically as at 11 to receive the inner bowl 12, which is turned to fit closely in 10, and is provided at its upper end with a flange 13 seating upon the upper edge of the bowl 10 and having its peripheral surface flush with the peripheral surface of the bowl 10. The inner bowl 12 is also preferably made of briar wood and is bored cylindrically, as at 14, to form a bowl for burning

the tobacco. Around the outer surface of the inner bowl 12 are two peripheral grooves 15 and 16, spaced axially along the bowl so that radial holes 17 and 18, of which there are two to each groove one at each end, connecting these grooves with the interior of the tobacco bowl, occur half-way down and at the bottom of the tobacco bowl.

The peripheral grooves 15 and 16 do not extend entirely around the bowl but each has a length of 270 degrees the centers of the groove measured angularly, being diametrically opposite and the ends of the groove overlapping for 90 degrees at the ends. Communication between grooves 15 and 16 and the pipe stem holes is obtained by means of an axially extending semi-circular groove 19 drilled in the inner surface of the outer bowl 10, directly in line with the pipe stem hole 20. The semi-circular groove 19 extends upward from the pipe stem hole 16 just far enough to overlap groove 15. Plug 21 provides means for stopping the hole made in the bottom of the pipe body when groove 19 is drilled.

It is evident from the above description that with the inner bowl in the position shown in Fig. 1 that a smoke passage is provided through holes 17, grooves 15, 19 and stem hole 20. A section through Fig. 2, at 3—3 is shown in Fig. 3, which shows that groove 15 is in position to communicate with groove 19 and therefore the smoke is drawn from the pipe over this path. Fig. 4, 30 which is a section through Fig. 2 at 4—4 shows that groove 14 does not communicate with the groove 19 in this position, and therefore no smoke is drawn through holes 18 at the bottom of the tobacco bowl. This is the proper position for the inner bowl during the first half of the smoke and since the smoke is not drawn through the tobacco in the lower half of the bowl it remains fresh and dry.

When the tobacco in the upper half of the bowl is smoked or nearly so, the inner bowl is rotated through approximately 180 degrees. With the bowl in this position the smoke is drawn through holes 18 and grooves 16, 19 and stem hole 20 and no smoke is drawn through holes 17 and groove 13, as it is not in communication with groove 19. The proper position of the inner bowl for each position of the smoke is indicated by different sized holes drilled in the outer surface of the bowl, as at 22 and 23, the smaller hole, when on the stem side, indicating that the bowl is set for the first half pipeful, and the large hole indicating the setting for the last half pipeful. It should be noted that the position of the inner bowl for the first or last half pipeful is not critical as the

valve section of the grooves in either position is effective through practically 90 degrees of bowl position. The space 24 at the bottom of the outer bowl and the absorbent material 31, such as cotton placed therein are provided for the collection and retention of saliva and other moisture which would otherwise tend to collect in the pipe stem hole 20 and then be drawn into the smoker's mouth. As the pipe is ordinarily held in an inclined position with the bowl lower than the stem, all excess moisture will collect in this space which prevents it from being drawn into the smoker's mouth since it is not in the path over which smoke is drawn from the pipe.

15 In Fig. 5 I have shown a modification in which the bowl 10 is provided with an axially extending hole 25, having ports 26 and 27 to communicate with the respective grooves 15 and 16 of the inner bowl 12. Plugs 28, 29 and 30 provide means 20 of stopping the holes made in the bowl when the respective hole 25 and ports 26 and 27 are drilled.

25 The present invention as above described is completely effective in providing a uniform smoke as it prevents the moisture and other volatile products in the smoke from condensing in the tobacco in the lower part of the bowl. In the ordinary pipe these products condense in the tobacco and consequently as the smoke progresses it becomes stronger and stronger and it is difficult to force the tobacco to burn. As a result 30 few smokers attempt to smoke all the tobacco in the ordinary pipe and consequently more frequent reloading is required, and full and economical use of the tobacco is not obtained.

35 In the present invention, since the tobacco in the bottom of the bowl is kept fresh and dry, the smoke from this position of the pipeful is as mild as from the first half and the tobacco is all readily burned thus giving a longer and more economical smoke.

40 The present invention is completely effective in providing a uniform, mild and full flavored smoke. It has always been assumed by pipe makers and smokers that removing the tar and moisture products in the smoke would result in the most desirable condition, but experience has shown that effective filters remove too much or 45 too many of the volatile products and leave the smoke without sufficient flavor or satisfying capacity. The experience and conclusion of the inventor is that the desired flavoring of pipe smoke can best be accomplished by passing the smoke through passages, the surfaces of which are coated with a relative pure form of the tar found in tobacco smoke. The concentrated tar 50 has absorbent properties which enable it to remove additional tar from the smoke and give the smoke the desired flavor. The presence of moisture to any extent is disadvantageous to this action.

55 The temperature of the flavoring grooves around the inner bowl of the present invention, has an important effect upon the quality and flavoring ability of the tar that forms there. Too high a temperature causes the tar to dry out and 60 too low a temperature allows too much moisture to condense, both conditions being unfavorable to the best action of the pipe. The size and thickness of the inner bowl affects the temperature of the grooves. An inner bowl bore of $\frac{3}{4}$ inch and 65 a thickness of $\frac{1}{2}$ inch with grooves not more than $\frac{1}{4}$ inch deep have been found quite satisfactory when the pipe is made of briar.

70 The action of ordinary pipes bears out the above conclusions. It is well known that pipes 75 must be broken in before they smoke satisfac-

tory and that they smoke better if given a rest now and then. Breaking in a pipe consists of getting a coat of tar (diluted in ordinary pipes and concentrated in the present invention) on the surface of the smoke passage. When ordinary pipes are smoked in such a way that the coating has no chance to dry out it becomes so diluted that it has no acceptable flavoring action. When the pipe is unused for a time the flavoring action is restored. The present invention is not 10 subject to this disadvantage.

15 Briar is the pipe wood that experience and tradition have indicated is best. The apparent explanation of this is that tobacco tar has a greater affinity for briar wood than for other woods or 20 materials and forms upon it more readily. Thus a briar pipe stands a better chance of acquiring a coat of tar than other woods or materials.

25 From the above conclusions it is evident that a really satisfactory pipe must have effective elements for (a) insuring the formation of tar in a relatively concentrated form (b) a sufficient length of tar coated smoke passage to properly flavor the smoke (c) withdrawing the smoke from the tobacco in such a way that the smoke will be 30 of uniform quality throughout the pipeful (d) controlling the moisture that always collects, so that it will not work into the flavoring grooves, will not cause bubbling, and can be conveniently removed.

35 In the present invention both conditions (a) and (b) are effectively and inherently provided in the peripheral grooves that collect the smoke. There is no disadvantageous condensation of moisture in them and tar does form and accumulate there in the proper concentration. These grooves also provide a sufficient length of tar 40 coated smoke passage to give the desired flavoring action.

45 Condition (c) is effectively provided in the feature where the smoke is withdrawn from the tobacco bowl at two different levels. Thus the smoke is sufficiently uniform that the other features of the pipe are not subject to widely varying conditions that might prevent them from functioning in the desired manner.

50 Condition (d) is effectively provided in the moisture well and absorbent material placed therein. Tobacco smoke contains a considerable amount of moisture and when removed in the degree the present invention removes its absorption becomes important. Without a well the water would collect in such quantity in the stem that it would gurgle and be drawn into the smoker's mouth. If allowed to collect loosely in the well, ordinary handling of the pipe causes it to work up into the flavoring grooves, particularly the lower one. Loose water is also difficult to clean from the pipe as it cannot be emptied or 55 shook out satisfactorily since it sticks to the surface of the bowl. The provision of an absorbent material, such as cotton, collects and retains the moisture in the well to a satisfactory degree and its removal is accomplished by replacing the soaked absorbent with fresh material.

60 The present invention is easily and quickly broken in because the tar deposited in the pipe increased perceptibly with each pipeful. Since the breaking in process consists of getting a sufficient coating of tar the normal breaking in 65 process can be entirely obviated by artificially coating the proper surface with tar extracted separately from tobacco smoke.

70 I have illustrated and described preferred and 75 satisfactory embodiments of the invention, but

it will be obvious that changes may be made therein, within the spirit and scope thereof, as defined in the appended claims.

Having thus described my invention what I claim and desire to secure by Letters Patent is:—

1. In a smoking pipe, an outer bowl having a chamber, a stem for said outer bowl, said outer bowl having an axially extending passage forming communication between said chamber and the stem passage, an inner bowl rotatably engaged in the chamber of said outer bowl, said inner bowl having a hole at one level, and another hole at another level, circumferentially extending means at said first level forming a passageway between said first hole and said axial passage in one position of rotation of said inner bowl, and means also at said level adapted to close said axial passage in another position of rotation of said inner bowl, circumferentially extending means at said other level forming a passageway between said other hole and said axial passage in one position of rotation of said inner bowl, and means also at said other level adapted to close said axial passage in another position of rotation of said inner bowl, said closure means at one level being radially offset with respect to said closure means at said other level.

2. In a smoking pipe, an outer bowl having a chamber, a stem for said outer bowl, said outer bowl having an axially extending passage forming communication between said chamber and the stem passage, an inner bowl rotatably engaged in the chamber of said outer bowl, said inner bowl having a plurality of holes at one level, and another plurality of holes at another level, circumferentially extending means at said first level forming a passageway between said first plurality of holes and said axial passage in one position of rotation of said inner bowl, and means also at said level adapted to close said axial passage in another position of rotation of said inner bowl, circumferentially extending means at said other level forming a passageway between said other plurality of holes and said axial passage in one position of rotation of said inner bowl, and means also at said other level adapted to close said axial passage in another position of rotation of said inner bowl, said closure means at one level being radially offset with respect to said closure means at said other level.

3. In a smoking pipe, an outer bowl having a chamber, a stem for said outer bowl, said outer bowl having an axially extending passage forming communication between said chamber and the stem passage, an inner bowl rotatably engaged in the chamber of said outer bowl, said inner bowl having a hole at one level, and another hole at another level, circumferentially extending groove means at said first level forming a passageway between said first hole and said axial passage in one position of rotation of said inner bowl, and means also at said level adapted to close said axial passage in another position of rotation of said inner bowl, circumferentially extending groove means at said other level forming a passageway between said other hole and said axial passage in one position of rotation of said inner bowl, and means also at said other level adapted to close said axial passage in another position of rotation of said inner bowl, said closure means at one level being radially offset with respect to said closure means at said other level.

4. In a smoking pipe, an outer bowl having a

chamber, a stem for said outer bowl, said outer bowl having an axially extending passage forming communication between said chamber and the stem passage, an inner bowl rotatably engaged in the chamber of said outer bowl, said inner bowl having a hole at one level, and another hole at another level, circumferentially extending groove means provided in said inner bowl at said first level forming a passageway between said first hole and said axial passage in one position of rotation of said inner bowl, and means also at said level adapted to close said axial passage in another position of rotation of said inner bowl, circumferentially extending groove means provided in said inner bowl at said other level forming a passageway between said other hole and said axial passage in one position of rotation of said inner bowl, and means also at said other level adapted to close said axial passage in another position of rotation of said inner bowl, said closure means at one level being radially offset with respect to said closure means at said other level.

5. In a smoking pipe, an outer bowl having a chamber, a stem for said outer bowl, said outer bowl having an axially extending groove forming communication between said chamber and the stem passage, an inner bowl rotatably engaged in said outer bowl, said inner bowl having a hole at one level, and another hole at another level, circumferentially extending means at said first level forming a passageway between said first hole and said axial passage in one position of rotation of said inner bowl, and means also at said level adapted to close said axial passage in another position of rotation of said inner bowl, circumferentially extending means at said other level forming a passageway between said other hole and said axial passage in one position of rotation of said inner bowl, said closure means at one level being radially offset with respect to said closure means at said other level.

6. In a smoking pipe, an outer bowl having a chamber, a stem for said outer bowl, said outer bowl having an axially extending hole and laterally extending parts at a plurality of levels forming communication between said chamber and the stem passage, an inner bowl rotatably engaged in said outer bowl, said inner bowl having a hole at the level of one of said parts, and another hole at the level of another of said parts, circumferentially extending means at said first level forming a passageway between said first hole and said axial passage in one position of rotation of said inner bowl, and means also at said level adapted to close said axial passage in another position of rotation of said inner bowl, circumferentially extending means at said other level forming a passageway between said other hole and said axial passage in one position of rotation of said inner bowl, and means also at said other level adapted to close said axial passage in another position of rotation of said inner bowl, said closure means at one level being radially offset with respect to said closure means at said other level.

7. In a smoking pipe, an outer bowl having a chamber, a stem for said outer bowl, said outer bowl having an axially extending passage forming communication between said chamber and the stem passage, an inner bowl rotatably engaged in the chamber of said outer bowl, said in-

5 10 15 20 25 30 35 40 45 50 55 60 65 70 75

ner bowl having a hole at one level, and another hole at another level, circumferentially extending means at said first level forming a passageway between said first hole and said axial passage in one position of rotation of said inner bowl, and means also at said level adapted to close said axial passage in another position of rotation of said inner bowl, circumferentially extending means at said other level forming a passageway between said other hole and said axial passage in one position of rotation of said inner

bowl, and means also at said other level adapted to close said axial passage in another position of rotation of said inner bowl, said closure means at one level being radially offset with respect to said closure means at said other level there being a well in the lower end of said outer bowl beneath said inner bowl, in communication with said axially extending passage and moisture absorbing material in said well.
